ELECTROMAGNETIC TRANSLATING DEVICE

Benjamin B. Bauer, Chicago, Ill., assignor to
 S. N. Shure and Frances Shure, trustee, doing
 business as Shure Brothers, a partnership

Application February 7, 1941, Serial No. 377,855

17 Claims. (Cl. 179—100.41)

This invention relates to an electromagnetic translating device and more particularly to a phonograph recorder or reproducer.

The recorders of the prior art have been generally characterized by heavy magnetic structures and relatively complicated vibratory systems. As a rule, the magnet has pole pieces of complex shape whose fabrication is inexpensive. The assembling of the entire device is inherently expensive also.

The vibratory portions of the recorders of the art are either mechanically complex and expensive or have undesirable vibratory characteristics.

The present invention provides a construction which is mechanically simple, which has desirable and closely controllable characteristics in quantity production and which is sturdy. One important feature of the invention resides in the magnetic circuit construction whereby lightness, accuracy, economy and magnetic efficiency are attained. Another important feature of the invention resides in the vibratory system. By virtue of the construction of the vibratory system, extreme mechanical simplicity and highly desirable vibratory characteristics result.

Mechanical simplicity in a vibratory device is highly desirable from a theoretical angle. Each discrete physical element in a system has its own mass and elasticity. The more elements there are in a vibratory system, the greater the problem of resonance and transfer of energy from one element to another.

The present invention in general contemplates a compact permanent magnet having a general block shape and provided with pole faces. I prefer to use cobalt bearing alloys as Alnico or similar alloys having high coercive force and relatively low remanence. In using such alloys, I prefer to have the length of the magnet; i. e., the dimension along the interior flux path, of the same order as the transverse dimension or dimensions and preferably equal or even less than the transverse dimension. In such a magnet, the projected pole area becomes substantial and comparable to the projected area of the remainder of the magnet. Thus full advantage of the properties of modern magnet materials is taken. The magnet materials are generally hard so that a finished pole face is easily, accurately and economically attained by grinding. The main supporting structure of the device or base consists of the pole pieces. Since these are of soft steel, they may be punched or stamped as desired. The

entire vibratory system may be supported between the pole pieces.

The vibratory system consists of a combined armature and torsion spring piece and a rigid drive rod upon which a needle may be mounted. The construction is exceedingly simple and concentrates substantially all of the elasticity of the system within the one armature and spring piece. This is important since elasticity is one of the determinants of the vibratory characteristics of the system. The elasticity and mass of the armature and spring piece may be closely controlled in production. This results in accurate control of the overall characteristics as will be apparent later. The physical coupling between the drive rod and armature-spring piece is accomplished in a simple but highly effective manner so that for practical purposes the two may be considered as one.

The entire device is noteworthy for the ease and lack of delicacy necessary for assembling. All parts to be assembled are firmly and accurately retained in position and the final product is dependent upon a few manufacturing tolerances rather than any assembly technique. In one species of the invention, however, there is provided a simple adjustment for positioning the armature in its air gap.

Referring to the drawings:

30 Figure 1 is a sectional elevation of a recorder;
 Fig. 2 is a section along 2—2 of Fig. 1;
 Fig. 3 is a transverse section along broken line 3—3 of Fig. 2;
 Fig. 4 is a front elevation of the recorder with the locking screw cut away;
 Fig. 5 is a plan view of a modified form of recorder;
 Fig. 6 is a sectional elevation along line 6—6 of Fig. 5;
 Fig. 7 is an elevation from the rear;
 Fig. 8 is a perspective detail of the magnet and pole pieces of the modification;
 Fig. 9 is a sectional plan view of a different modification;

45 Fig. 10 is a side elevation of the recorder of Fig. 9; and
 Fig. 11 is a section on 11—11 of Fig. 10.
 Referring to Figs. 1 to 4 inclusive, a magnet 10, preferably of some cobalt bearing alloy such as Alnico has two pole faces 11 and 12 ground smooth. As shown, the magnet is rather squat with its length as its shortest dimension and has its pole faces at each end. Any desired shape of magnet may be provided. In general, the projected pole areas, here the areas of the faces,

are comparable to the projected areas of the remaining magnet sides. Disposed on the magnet pole faces are soft iron or soft steel frame members 13 and 14 maintained in position by non-magnetic rivets 16 of brass, aluminum or the like. The frame members are thin enough to be stamped or punched out of sheet metal. By using highly permeable metal for the pole pieces the flux density therein may safely be higher than the normally low density in the magnet proper.

Frame members 13 and 14 extend beyond magnet 10 to enclose the various parts of the recorder. While the frame members are shown as generally flat pieces lying in generally parallel planes it is to be understood that they may have any desired shape and lie in any desired position relative to each other depending upon the mechanical details of construction. As shown here, frame members 13 and 14 extend away from magnet 10 for a distance and are provided with blocks 18 and 19 of non-magnetic material. Non-magnetic rivets 20 maintain blocks 18 and 19 in position. Blocks 18 and 19 may be of metal or not and preferably are rigid enough so that a strong structure will result.

By having frame members 13 and 14 extend beyond magnet 10, a region 21 is provided between them in which the vibratory portion of the recorder may be disposed. Adjacent region 21, frame members 13 and 14 have lateral extensions 22 and 23 bent out of the plane of the members proper and extending toward each other to form an air gap 24 therebetween. A corresponding pair of extensions 22' and 23' are provided on the other side of the two frame members and form a second air gap 25. While two air gaps are shown, it is clear that one set of extensions may be omitted and leave only one air gap.

Operating within the two air gaps are two portions 27 and 28 of a unitary armature whose center section 30 is extended to form a torsion tail piece 31. This combined armature and spring is of elastic magnetic material and may be of soft iron or soft steel. As shown in the drawings, the armature-spring member has a generally T-shape. While the armature portions 27 and 28 are shown as equal and rectangular, it is clear that they may have any shape and length. Thus by tapering the armature portions, the stiffness and mass may be varied. In fact by controlling the shape and dimensions of the armature and tail portions, any desired vibratory characteristic may be obtained. In any event, this unitary piece is preferably a stamping and may be duplicated in production to within close limits.

Tail piece 31 is suitably apertured at an end thereof and is rigidly supported between sleeves 32 and 33 by a bolt 34 threaded into top frame member 13. Any other rigid support for tail piece 31 may be provided. The support disclosed however is desirable since sleeve 33 is the only piece requiring accuracy. It is evident that the rest position of the armature portions in the air gaps is determined by sleeve 33.

Center section 30 of the armature spring piece supports a driving rod 35 by passing through a transverse slot 36 in the end of the rod. This slot 36 is preferably so dimensioned that armature section 30 fits tightly therein. Thus the grip between the two parts extends over the entire opposing surfaces. Rivets 37 and 38 extending transversely through the bifurcated rod end 75

and armature section 30 hold the two tightly together. Other means as welding or soldering may be provided. It is evident therefore that rod 35 is supported for oscillation about its longitudinal axis.

Drive rod 35 is preferably cylindrical and may be of aluminum or any other metal, magnetic or non-magnetic. Irrespective of the length of rod 35, the torsional elasticity is negligible. Ordinarily the only factor, from a vibratory angle, present in rod 35 is inertia and this is susceptible to close control in fabrication. The rod is simple and may be made accurately in quantity. In fact, by using aluminum or other light weight material for the drive rod and rivets 37 and 38, the tolerances may be increased without adversely affecting the vibratory characteristics.

Rigid drive rod 35 is here shown as having substantial length and provided with some support for its free end. This consists of a sleeve 40 of rubber or other resilient material disposed around the free end of rod 35 and supported in registering semi-circular channels 41 in blocks 18 and 19.

This resilient support for the drive rod 35 permits the rod to oscillate about its longitudinal axis. The sleeves 32 and 33 furnish a rigid support for the other end of the assembly comprising the drive rod 35 and the elastic spring 30. There is no intermediate support. The spring provides torsional compliance for the drive rod and, in addition, since the spring is in the form of a flat leaf spring with its thin dimension extending vertically and its wide dimension extending horizontally (in the position of the device shown in Fig. 1), it possesses elastic compliance in a vertical direction and substantially no compliance in a horizontal direction.

The free end of drive rod 35 is provided with an axial bore 42 extending inwardly for a substantial distance and threaded to accommodate a locking screw 43. Transverse to bore 42 at an intermediate portion of rod 35 is a needle channel 45 into which a needle 46 may be clamped by screw 43. Needle 46 as a rule is of hard steel so that screw 43 does not bite into it. Needle 46 may pass through an aperture 47 in bottom frame member 14.

The cutter or recorder in use is normally disposed in the position shown in Fig. 1 where frame member 13 is on top. As a rule, the device is pivotally or movably mounted for vertical motion to and from the record. It has been found in case of accidental dropping, the needle point ordinarily strikes first and drives the needle up to cause slippage. To cushion the shock, a rubber or similar flexible pad 50 is disposed below top frame piece 13 and above the needle bearing portion of the drive rod. Hence the cutter is protected against damage. Pad 50 also functions normally as a stop when inserting a needle.

Disposed between top and bottom frame members 13 and 14 are spools 57 and 58 carrying the voice current coils 59. Where only one air gap and armature section are provided, only one spool would be present. The spools have narrow channels 60 through which armature sections 27 and 28 are threaded and are disposed as close as possible to the air gaps.

Rubber sleeves 61 and 62 around drive rod 35 are thick enough to reach the sides of the spools and may provide spool spacing means as well as some non-resonant damping. Slots 63 may be provided in the pole pieces at the air gaps and

resilient dissipative pads disposed therein and extend out to the armature.

Referring now to Figs. 5 to 8 inclusive, a construction is shown where the vibratory system is supported in a different form. A compact block shaped magnet 70, preferably similar in properties to magnet 10, has finished pole faces 71 and 72. Soft steel pole pieces 73 and 74 are disposed against the opposite pole faces 71 and 72. Said pole pieces have extensions 75 and 75' and U-shaped end portions 76 and 76' terminating in pole tips 77, 77' and 78, 78' and forming air gaps 79 and 80.

The pole pieces and magnet may be maintained intact in any manner and as shown are pressed together by a spring U-shaped frame member 82 of sheet brass, aluminum or other non-magnetic metal. The arms 83 and 83' of the frame member may have retaining screws 84 passing through and engaging the pole pieces.

Frame member 82 has its bight portion 85 provided with a centrally disposed generally semi-circular longitudinal channel 86. This channel may be formed by shaping the frame metal. Resting within said channel is the drive rod portion of the vibratory system and consists of rod 90 having spaced resilient sleeves 91 and 92 with curved metal grips 93 and 94 almost surrounding the rubber sleeves. The drive rod assembly is maintained in position by spaced metal straps 95 and 96 extending transversely thereof and having the ends thereof rigidly fastened to frame member 82 by screws 97. The object of the drive rod mounting is to provide a generally resilient mounting similar in properties to the mounting between blocks 18 and 19 in Fig. 1.

One end 99 of drive rod 90 is bifurcated and grips a flat spring armature 100 extending upwardly at right angles to said rod. The general rod and armature construction is the same as in Figs. 1 to 4 inclusive, except that armature 100 has a tongue 101 at the extreme end. As shown in Fig. 7, armature 100 extends through both air gaps 79 and 80. Drive rod 90 has a transverse needle channel 103 in which a needle 104 may be clamped by screw 105 operating in axial threaded bore 106. Needle 104 may extend through a suitable aperture 107 in frame channel 86.

While the drive rod mounting may be relied upon to furnish a restoring force to the armature to position the same in the center of the air gaps, nevertheless additional means is preferred. This means may consist of a resilient strip 110 into which armature tongue 101 may be disposed. The ends of strip 110 may be anchored by screws 111 and 112 engaging the pole pieces. Strip 110 may be of rubber or the like and is preferably adjustably mounted to permit accurate centering of armature 100. Because strip 110 extends on both sides of tongue 101, it is clear that the damping force of the strip is exerted both in compression and tension.

Surrounding armature 100 is a voice current coil 115 carried on a spool and firmly wedged in between the U's of the pole pieces.

Figs. 9 to 11 inclusive show a modification having certain of the features of both preceding constructions. Thus the magnet and pole piece construction follow lines of Figs. 1 to 4 inclusive. The vibratory system differs both in the mounting and damping. Armature portions 127 and 128 have a center section 130 extended to form a torsion piece 131 and this has lateral 75

extensions 132 and 133. Thus the armature and spring member has a generally H-shape. The supports consist of screens 134 to 137 inclusive in spaced opposed pairs threaded in top and bottom frame members 13 and 14. The points of support for the spring lateral extensions 132 and 133 may be separated as widely as desired or may be continuous across the entire spring metal. By having the type of support as shown, the position of each armature portion in each air gap may be controlled.

Armature portions 127 and 128 have tongues 138 and 139 at their free ends passing through slits in resilient strips 140 and 141. Each strip, like the corresponding strip in Fig. 5, is anchored at the ends by screws.

In this modification, as in that of Figs. 1 to 4, the spring member provides torsional and vertical compliance and substantially no horizontal compliance.

In the various modifications, the drive rod has been disclosed as a rod of uniform cross-section throughout its effective length. This construction is the simplest to make and may suffice for many purposes. However, in the event that torsional elasticity in the drive rod is to be provided to a substantial degree or increased above that due to uniform cross section then a departure from cross sectional uniformity may be provided. Obviously the circular cross-section may be reduced to a small circular section or changed to a narrow rectangular section. In other words, between the armature mounting part of the rod and needle carrying part thereof a short length of the rod may be flattened, reduced to a smaller rod section or treated in some manner to introduce a local torsional compliance.

What is claimed is:

1. In an electromagnetic translating device, the combination of a magnetic circuit having at least one air gap, a drive rod oscillatable about its longitudinal axis, means consisting of a metallic torsion spring joined to said drive rod and extending from an end thereof in a direction longitudinally of said drive rod for supporting said end of said drive rod and biasing said rod to a predetermined at rest position from which it may be oscillated, said torsion spring possessing elastic compliance in a direction transversely thereof and being substantially rigid in a direction normal to said direction of compliance, a substantially rigid support for said torsion spring at a portion thereof spaced from said end of said drive rod, a support for said drive rod at a portion thereof spaced from said end of said drive rod, an armature carried by said rod and consisting of a flat member extending transversely from said rod into said air gap, at least one voice current coil around said armature, and means on said rod between said support for said rod and said end of said rod joined to said torsion spring for supporting a stylus member in a position with its axis extending generally in the direction of said torsion spring transverse compliance.

2. In an electromagnetic phonograph translating device, the combination of a magnetic circuit having at least one air gap, a drive rod oscillatable about its longitudinal axis, a unitary flat metallic member having a resilient spring portion for supporting and torsionally biasing said rod and an armature portion extending into said air gap, said spring portion having elastic compliance in a direction normal to the plane of said flat member and being substantially rigid in a direction parallel to said plane, a voice current coil around

said armature, and means on said rod for supporting a recording stylus with the axis of said stylus extending generally in the direction of said elastic compliance of said flat member.

3. In an electromagnetic type of phonograph recorder, the combination of a magnetic circuit having a pair of air gaps, a generally T-shaped flat piece of magnetizable spring metal, the transverse portion of said T forming a pair of armature sections adapted to operate within said air gaps, the remaining portion of said T adapted to function as a torsion spring, means for rigidly supporting said T-shape section at the free end of said torsion section, a drive rod oscillatable about said torsion axis, means for rigidly supporting said drive rod on said T at the junction of said two sections, said junction being otherwise unsupported, a voice coil around each armature section, and means on said rod for supporting a recording stylus.

4. The structure of claim 3 wherein flexible supporting means for the free end of said drive rod is provided.

5. The structure of claim 3 wherein said driving rod is slotted at the end and is adapted to fit tightly over the T section so that a rigid unitary construction results.

6. In an electromagnetic type of recorder, a block shaped permanent magnet having opposite sides finished as pole faces, flat pole pieces rigidly secured to said pole faces and extending beyond said magnet in spaced substantially parallel planes, rigid means disposed between the free ends of said pole pieces for maintaining the same in spaced relationship, each pole piece having an extension on each side thereof extending toward the opposing pole piece to form two pairs of juxtaposed extensions with an air gap between each pair of such extensions, a vibratory system including a T-shaped spring and a rigid drive rod, the main leg of said T-shaped spring being a torsion spring with the two arms being armatures, said rod and torsion portions being rigidly joined but otherwise unsupported and means for supporting said torsional spring at one end.

7. The structure of claim 6 wherein said drive rod is adapted to be oscillated along its longitudinal axis and wherein said drive rod passes through said rigid means and is supported in said rigid means by resilient means.

8. An electromagnetic type of recorder comprising a magnetic circuit including at least one air gap, a horizontal drive rod having attached thereto an armature operating in said gap, metallic spring means for supporting one end only of said rod, said means having torsional and vertical compliance and substantially no horizontal compliance, thereby permitting torsional and vertical rod vibration only, a resilient support for the other end of said rod and a stylus carried by said rod and extending downwardly therefrom.

9. The structure of claim 8 wherein said drive rod has a transverse channel for said stylus and wherein a rubber backing member above said stylus is provided.

10. The construction of claim 1 in which the metallic torsion spring is of thin flat shape and the stylus supporting means is adapted to support the stylus with the axis thereof generally perpendicular to the plane of the broad surface of said spring.

11. In an electromagnetic translating device, the combination of a magnetic circuit having at least one air gap, a drive rod oscillatable about its longitudinal axis, means consisting of a metallic torsion spring joined to said drive rod and ex-

tending from an end thereof in a direction longitudinally of said drive rod for biasing said rod to a predetermined at rest position from which it may be oscillated, said spring having leg sections extending transversely therefrom at a portion thereof spaced from said end of said drive rod, substantially rigid supports for the extending portions of said leg sections, an armature carried by said rod and consisting of a flat member extending transversely from said rod into said air gap, at least one voice current coil around said armature, and means on said rod for supporting a stylus member.

12. In an electromagnetic translating device, the combination of a magnetic circuit having at least one air gap, a drive rod oscillatable about its longitudinal axis, means consisting of a metallic torsion spring joined to said drive rod for biasing said rod to a predetermined at rest position from which it may be oscillated, said spring having leg sections extending transversely therefrom, substantially rigid supports for the extending portions of said leg sections, an armature carried by said rod and consisting of a flat member extending transversely from said rod into said air gap, at least one voice current coil around said armature, and means on said rod for supporting a stylus member.

13. The construction of claim 12 in which the armature consists of a thin flat metallic spring member having compliance, and means are provided for restraining the end portion of the armature against the vibration of said end portion.

14. In an electromagnetic translating device, the combination of a magnetic circuit having at least one air gap, a drive rod oscillatable about its longitudinal axis, means comprising a metallic torsion spring joined to said drive rod and extending in a direction longitudinally of said drive rod for biasing said rod to a predetermined at rest position from which it may be oscillated, an armature consisting of a thin flat metallic spring member having compliance extending transversely from said rod into said air gap, said rod being joined in vibration transmitting relation to said armature, means for restraining the end portion of said armature against the vibration of said end portion, at least one voice coil around said armature, and means on said rod for supporting a stylus.

15. In an electromagnetic translating device, the combination of a magnetic circuit having at least one air gap, a drive rod oscillatable about its longitudinal axis, an armature consisting of a thin flat metallic spring member having compliance extending transversely from said rod into said air gap, said rod being joined in vibration transmitting relation to said armature, means for restraining the end portion of said armature against the vibration of said end portion, at least one voice coil around said armature, and means on said rod for supporting a stylus.

16. In an electromagnetic translating device, a permanent magnet having pole faces on opposite sides thereof, pole pieces fixed to said pole faces respectively and extending beyond said magnet in spaced opposing relation to each other, each of said pole pieces having at least one extension bent toward the opposing pole piece at points spaced from said magnet to form at least one air gap between said extensions, said extensions having sides of relatively large area and edges of relatively small area, an edge of each of said ex-

tensions being disposed toward said magnet, and an armature supported in said air gap.

17. In an electromagnetic translating device, a permanent magnet having pole faces on opposite sides thereof, pole pieces fixed to said pole faces respectively and extending beyond said magnet in spaced opposing relation to each other,

each of said pole pieces having a pair of extensions bent toward the opposing pole piece at points spaced from each other and from said magnet to form a pair of air gaps between said extensions, and armature means supported in said air gaps.

BENJAMIN B. BAUER.

CERTIFICATE OF CORRECTION.

Patent No. 2,356,810.

August 29, 1944.

BENJAMIN B. BAUER.

It is hereby certified that error appears in the above numbered patent requiring correction as follows: In the grant, line 2, for the word "TRUSTEES" read --TRUSTEE--; line 13, for "as Trustees" read --Trustee--; page 1, first column, line 8, for "inexpensive" read --expensive--; line 37, and second column, line 50, insert quotation marks before and after the word "Alnico"; page 3, second column, line 3, for "screens" read --screws--; and that the said Letters Patent should be read with this correction therein that the same may conform to the record of the case in the Patent Office.

Signed and sealed this 30th day of January, A. D. 1945.
